UNITED STATES PATENT OFFICE.

FREDRICK R. DRINKHOUSE AND EDWARD ZIESCHE, OF SAN FRANCISCO,
CALIFORNIA.

SAFETY-LOCK FOR GAS-BURNERS.

SPECIFICATION forming part of Letters Patent No. 372,789, dated November 8, 1887.

Application filed March 21, 1887. Serial No. 231,784. (No model.)

To all whom it may concern:

Be it known that we, FREDRICK R. DRINKHOUSE and EDWARD ZIESCHE, citizens of the United States, residing in the city and county of San Francisco and State of California, have invented certain new and useful Improvements in Safety-Locks for Gas-Burners; and we do hereby declare that the following is a full, clear, and exact description of our said invention, reference being had to the drawings that accompany and form a part of this specification.

Our invention has for its object to provide a safety device for gas-burners which shall prevent the key from being improperly turned or set by careless or ignorant persons.

It consists in a novel locking device that is self-acting, and also in the combination, with such device, of a signal bell or alarm which shall produce sufficient sound at the time of turning the key and at the point when the gas is cut off to signify that the burner is safely turned, all as hereinafter fully described and specifically claimed.

In the following description reference is made by figures and letters to the accompanying drawings, in which—

Figure 1 is a side view of a gas-burner having our invention applied to it. Fig. 2 is a transverse section taken at about the line xx , Fig. 1. Fig. 3 is a view similar to Fig. 1, but with the key turned in the direction required to let on the gas. This view also shows the manner in which we apply a signal device to be operated by the movement of the key. Fig. 4 is a view similar to Fig. 3, with the key partly withdrawn and with one side of the key taken off.

A denotes in each figure the body of an ordinary gas-cock.

A' is a rim or fixed collar standing away from the body around the orifice in which the plug of the key works and having two notches or slots, $a a$, in its edge, one diametrically opposite to the other.

B' is the stem or plug of the key, with the usual aperture, b , through it, and B is the head of the key.

C is a spring pawl or lever pivotally secured by the pin d in a recess in the edge of the key, and having a curved end above the pivot

adapted by its shape and length to ride against the outside of the fixed rim A'.

C' is a projecting head on the lower end of the lever C, setting out from the edge of the key and bearing at the inner end within the body of the key against a coil-spring, E.

In the construction given in the drawings we have provided two of these locking-levers, as we consider the same preferable to a single lever for general purposes. It will be evident that in so far as the security of the lock is concerned one lever will prove to be quite as effective as two levers; but the use of the two levers will give greater durability, for if one lever becomes broken or gets out of order the other will act. We prefer, therefore, to provide our device with two locking-slots in the fixed rim and two catches on the key.

The construction given in the drawings is simple, compact, and durable. The levers are set into the edges of the key, so that in order to turn on the gas it is necessary to grasp the edges of the key instead of the face; but for the contrary movement, to shut off the gas, the key is seized flatwise, and the catches then drop into place as they move around the fixed collar.

The pins $d d$ pass through the body of the key, and the coil-spring sets into a recess provided in the key and between the lower ends of the two levers. The face-plate A' is removable for the purpose of repairs.

The alarm attachment is shown in Fig. 3. It is produced by fixing the small gong G on the collar above the key and attaching the striker g by a bent wire, g^2 , to the lever C. The movement of the lever as it drops into the slot a is sufficient to throw the striker against the gong, and the sound produced indicates that the key is properly turned into place. In this arrangement the single coil-spring serves to operate the striker as well as the levers.

Having thus fully described our invention, what we claim, and desire to secure by Letters Patent, is—

1. The combination, with the body of a gas-cock provided with a slotted rim fixed thereon, of the key or plug provided with a spring catch or pawl pivoted thereto, its upper end

being adapted to ride on the slotted rim and engage with the slots therein and its lower end projecting from the head of the key below the pivot, as set forth.

5 2. The combination, with the body of a gas-cock having a fixed collar or rim provided with notches or slots *a a*, of the key or plug provided with spring-levers pivoted thereto and projecting from the head thereof below the pivot and riding upon or engaged in the slots of said collar at their upper ends, substantially as set forth.

3. The combination, with the body of a gas-cock having a slotted collar or rim and a gong, 15 G, secured thereon, of the key having a lock-

ing lever or levers pivoted in and projecting from the head of said key below the pivots and their upper ends being adapted to ride on the slotted rim and engage the slots therein, and a striker attached to said lever or levers and adapted to be thrown against the gong on the rotary movement of the key, as set forth. 20

In testimony that we claim the foregoing we have hereunto set our hands and seals.
